MECHANICAL LEAD PENCIL

Charles R. Fargo, Beverly Hills, Calif.

Application September 25, 1939, Serial No. 296,383

2 Claims. (Cl. 120—21)

The hereinafter described invention relates to mechanical pencils, containing improvements by which the utility of pencils of this class is greatly extended; the new features and advantages of my invention permitting its entrance into a new field where the more expensive wooden pencils are now required to serve the purposes of draughtsmen, engineers, and architects.

Heretofore it has been practically impossible to meet the service demands in a mechanical bare lead pencil where the pressure in the lead is a principal factor in producing the character of line drawings required on vellum paper for blue-printing and/or duplication. The present disadvantages are a breakage of the leads when held against end movement and a slippage of the leads if held without breakage.

In the present mechanical pencils a strain is set up on the lead, the chuck arrangement being such as to cause the exertion of pressure in a circumferential line or small circumferential bearing around the lead which cracks it.

The primary object of my invention is to provide an improved structure of mechanical pencil wherein all of the disadvantages explained hereinabove are substantially entirely eliminated and a pencil which is superior to any known prior to my invention with regard to its resistance to the slippage of the lead and its ability to prevent breakage of same.

My invention is based on the discovery that a wedging action which will prevent breaking and slipping of the lead can be effected between the slotted tapered end of the tube holding the lead and the inner tapered surface at the end of the pencil barrel by preventing rotation of the lead-containing tube after the respective tapered surfaces contact each other, and thereafter forcing the slotted tapered tube end around the lead so that it will flatten out and form a longitudinally extending bearing of considerable extent along the surface of the lead. My improved structure is such that all torsional strain is taken off the lead when the tapered surface of the lead tube engages the tapered surface of the pencil end.

Now in order that my invention may be fully understood, reference is made to the illustrative embodiments shown in the accompanying drawing, and in which Fig. 1 is a view in side elevation of my improved pencil.

Fig. 2 is an enlarged sectional view taken on line 2—2, Fig. 1, showing the lead as secured in position by the improvements of my invention.

Fig. 3 is an enlarged fragmentary sectional 55

view of my invention at the lead point end showing the lead in released position.

Figs. 4, 5 and 6 are sectional end views taken on line 4—4, line 5—5, and line 6—6, respectively, of Fig. 1.

In the drawing, numeral 10 denotes the pencil barrel, and numeral 11 the chuck end of the barrel which in the present instance is a separate member secured thereto. Numeral 12 denotes the lead-containing tube, this being a continuously extending tube completely telescoping the lead. The chuck end 11 is formed with a comparatively long running tapered inner surface, while the outer surface of lead tube 12 is finished with a tapered surface complementary to the tapered surface of the end 11. The tapered surfaces of the respective members 11 and 12 are made with a relatively small degree of angularity, to assist the wedge action therebetween.

As distinguished from pencils of prior use, the lead tube 12 of my invention is made with a relatively thin tube wall and provided with slots 12a, which run a considerably greater distance along the tube wall than now possible to use in present pencils. My purpose is to provide a flexibility at the tapered lead gripping end of the tube 12 which will permit of its compression when forced into the inner tapered surface of the chuck end 11 and a flattening out so that the lead tube will present a cylindrical surface bearing against the lead. In order to force the flexibly formed end of tube 12 into its bearing engagement with the inner surface of chuck 11, I have mounted the tube 12 into a head 13 which carries it. The tube 12 is slipped through the bore of head 13 and held endwise thereagainst by the tube collars 14 and 15. Tube 12 is free to rotate in the head 13. One end of the head 13 is provided with a running thread which is adapted to engage a similar running thread formed in the upper end of pencil barrel 10.

In the illustrated embodiments of my invention the pencil barrel 10 is made of plastic mouldable material such as Tenite, the chuck end 11 being inserted in the barrel during moulding. Plastic material is also moulded around the head 13, as denoted by numeral 16, so as to form a finishing cap over the upper end of tube 12. Numeral 17 denotes the lead as situated in lead tube 12.

Now in regard to the functioning of my invention and the new features and advantages arising therefrom. Referring to Fig. 2, which shows the lead in gripped position in the pencil. In operation the screwing in of the head 13 into

the pencil barrel 10, carries the tapered split end of lead tube 12 into contact with the tapered inner surface of chuck end 13. Immediately after the respective tapered surfaces contact each other, no further movement axially of the tube 12 takes place. Then upon continuing to screw in the head 13, the end thereof as bearing against the lead tube collar 14, is forced down and flattened out against the lead 17 in a wide bearing area as shown between arrows and denoted by f.

It will therefore be clear that all torsional strain on the lead tube 12 is relieved by reason of the head 13 being free to move around the lead tube 12 without turning the tube. It can be well understood in view of this, and as heretofore stated, that I can employ a light tube wall and secure the advantages of the extreme flexibility thereof at the lead gripping end which will permit the metal of the wall to hug in tight around the lead, and in fact without an excessive pressure between the tapered surfaces of the lead tube and chuck, which means that an undue screwing in of the head 13 is not required to force the metal of the lead tube around the lead in securely holding it against a pressure of the hand of a draughtsman in a comparable manner to that now commonly applied in the use of the relatively hard lead wood draughting pencil in producing the same character of lines on a drawing. In fact, I have found in the practical use of my improved pencil, when the screw head 13 is slackened back in its threaded engagement with the barrel 10, that the frictional engagement and compression of the metal of the lead tube around the lead will securely hold the lead against slippage; and although this manner of operating my pencil is not advocated, it is nevertheless desired to point out thereby the great tenacity of my structure in firmly holding the lead in tightly gripped position.

In Fig. 5 I have shown the released position of the lead in the pencil. In releasing the lead the head 13 is slackened back in its threaded engagement with the barrel 10, at which time the end of the head 13 is brought to bear against the collar 15 of lead tube 12, causing the separation

5 of the tapered frictionally engaging surfaces of the chuck 11 and tube 12; however, without twisting the lead tube and destroying its advantages, as the separation of the lead-holding surfaces is a direct pull without rotary movement of the lead tube.

I desire it to be understood that reasonable modifications may be made by me in adapting the improvements of the structure to the trade, and the scope of same is limited only to the extent of the appended claims.

I claim:

1. In a mechanical pencil having a barrel with an internally tapered chuck end, and a running thread on its opposite end, a lead containing unit adapted for reciprocation in said barrel comprising a continuously extending cylindrical tube substantially uniform in cross section having a compressible end beveled to a sharp knife-like edge and engageable with the inner tapered surface of the chuck, the other end of said tube having a head slipped over it, said head having a bore closely engageable with the outer cylindrical surface of the tube wall and a running thread integral therewith engageable with the threaded end of the pencil barrel, there being abutments on the tube wall and said head being rotatably confined on the tube wall by said abutments so that its ends are engageable therewith.

2. In a mechanical pencil having a barrel with an internally tapered chuck end, and a running thread on its opposite end, a lead containing unit adapted for reciprocation in said barrel comprising a continuously extending cylindrical tube substantially uniform in cross section, said tube having a compressible end engageable with the inner tapered surface of the chuck, said end being slotted longitudinally and tapered to a thin knife-like edge, the opposite end of said tube having a head swivelly mounted thereon, said head comprising a sleeve closely engageable with the outer cylindrical surface of the tube wall there being shoulders on the tube wall, and said head being confined between said shoulders so that its ends are engageable therewith.

CHARLES R. FARGO.
